UNITED STATES PATENT OFFICE.

JOHN WICKS AND DONALD D. MCKAY, OF RIVERSIDE, CALIFORNIA.

AUTOMATIC TELEPHONE SWITCH SYSTEM.

No. 852,004.

Specification of Letters Patent.

Patented April 30, 1907.

Application filed August 30, 1906. Serial No. 276,407.

To all whom it may concern:

Be it known that we, JOHN WICKS and DONALD D. MCKAY, citizens of the United States, residing at Riverside, in the county of Riverside and State of California, have invented a new and useful Automatic Telephone Switch System, of which the following is a specification.

This invention relates to improvements in automatic telephone exchange systems, and more particularly that type known as the "Strowger" system.

The principal object is to provide novel means of a simple nature, whereby the automatic selecting or exchange mechanism will connect ringing current-generating means to the different lines and to the different wires of a party line so that either party on such line may be called independently of the other.

Two embodiments of the invention are illustrated in the accompanying drawings, Figure 1 being a diagrammatic view of one form, while, Fig. 2 is a similar view of a modification thereof. Fig. 3 is a diagrammatic view of the form illustrated in Fig. 1, and showing one type of the Strowger system in greater detail, together with the improvements associated therewith.

Both of said embodiments are intended for use with the Strowger system, well known to those skilled in the art, and, in order to avoid confusion and illustrate the mechanism as simply as possible, all features of said system not intimately associated with the present invention have either been eliminated or merely indicated.

Referring first to the embodiment illustrated in Fig. 1, a portion of an automatic selector or exchange mechanism is shown, comprising first and second selector switches A and B, and a connector switch C. This latter includes banks of contacts 1 and 2, with which the usual wipers 3 and 4 co-operate. Connected to the connector switch C is a party line, which, as shown, comprises line wires 5 and 6, in which the party instruments D and E are located; one of said instruments being designated, for example, 1201, the other 1202. Each instrument includes a signal bell, respectively designated 7 and 8, and it will be noted that these bells are connected through the hooks 9 with the separate wires of the line, each being connected to one only of the wires, and said bells being grounded, as shown at 10. The line wires 5 and 6 are respectively connected directly to

certain of the contacts 1 and 2, and besides, are respectively and reversely bridged by wires 11 and 12 to the adjacent contacts 2 and 1. The remaining contacts may be connected in the same or any ordinary manner to other line wires, as 13.

Connected to one of the wipers, as 3, by a wire 14 is a switch 15, that is movable into and out of engagement with one pole 16 of a ringing current generator 17, that is grounded, as shown at 18. The usual ringing relay 19 is employed, which includes the armature 20, for throwing the switch 15 into and out of operation.

In the present embodiment, a calling station F is shown as connected by the usual wires r and v through the selector switches A and D to the connector C, said station including the signal button 21, the contact for which is grounded, as shown at 22. This button is in electrical connection through the wire v and selector switches with a magnet 23, and battery 24, that is also grounded, as shown at 25. The armature 26 of the magnet 23 constitutes a circuit-closing means for the ringing relay 19. Assuming, therefore, that the station F has selected the station D or "1201" to be called, the selecting mechanism is automatically operated in the usual well known manner, and the wipers 3 and 4 will stop upon the contacts 1 and 2, to which the line wires are directly connected, as shown in full lines, and this, therefore, connects the switch 15 with the line wire 5, to which the signal of the station D or "1201" is connected. If, now, the signal button 21 is pressed, the circuit through the magnet 23 will be closed, the ringing relay will be operated, and the switch 15 closed. This will cause the current from the generator 17 to pass through the wire 14, the wiper 3, the party line wire 5, and bell 7, and thence to ground, while the bell 8 of the other party is isolated. On the other hand, if the station E or "1202" is called, the wipers 3 and 4 will assume the positions indicated in dotted lines, in which case, the generator switch 15 will be in connection through the wiper 3, bridge wire 12, and line wire 6; with the bell 8 of station E, so that a call sent in from station F will operate the said bell 8 at station E, while the other party signal is now cut out. The wipers are, of course, in like manner, movable to their other contacts and thus perform their usual functions while serving in connection with the bridge wire and con-

tacts to effect independent connections with the party signals of a single line. It will be observed that the structure involves no material change on the part of the apparatus, as a whole, and that one ringing relay only is necessary, as heretofore, for each connector switch. Thus, practical means of a simple nature are provided for separately calling each party of a line.

In order to more clearly explain the arrangement above described, the same is shown diagrammatically in Fig. 3, in connection with one form of the Strowger system now in use. No claim is of course made to the mechanism or the arrangement involved in this Strowger system outside of its association or combination generally with the novel signal mechanism, as above set forth, and the more complete showing is made solely for the purpose of making our improvements in the signaling mechanism and its relation to the general system more clear and more easily understood by those skilled in the art. As far as practicable, the same reference designations, employed in Fig. 1, have been used in this illustration, as it is exactly the same arrangement, and the same parts are involved as is shown in said Fig. 1.

In Fig. 3, there is illustrated diagrammatically a complete circuit of the first selector A, the second selector B, the connector C, and part of a first selector G of the called station. The calling station is designated generally by the reference letter F. On the first selector A, there is the usual four pole switch, known as the "side switch", each pole of which makes contact with three different points. These poles are respectively numbered 28, 29, 30 and 31. The switch is operated in a well known manner by means of the armature of the magnet 32, commonly known as the "private magnet". The line wipers of the first selector, designated 33, 34 and 35, are fastened together, and are moved in a vertical direction by means of a magnet 36. A rotary motion is given to the wipers by a magnet 37. By this vertical and rotary motion, the wipers make contact with any one of one hundred lines terminating in the banks associated therewith, as is well known.

It will be observed that the vertical line *v* from the calling station connects with the switch 28 of the first selector, the dotted lines of said switch representing the normal position of the same. The line *v* is therefore connected through the switch 28 with the wire 38 to the relay 39, known as the vertical relay. This relay is furthermore connected through wire 40 to the spring 41 of the relay 42, commonly termed "the cut out relay", and from the same spring 41, connection is made with the main side of the battery 24 through the dotted lines 43. The rotary line *r*, from the calling station is con-

nected through the pole 29 of the side switch by wire 44 to the relay 45, known as the "rotary relay", which connects with the main battery through the wire 46, the springs of the relay 42, and the wire shown by the dotted lines 43.

As is well known, the Strowger calling device is so arranged that a number of impulses corresponding to the number called is first given over the vertical line *v*, after which follows an impulse over the rotary line *r*. Thus for example, if five be called, the calling device will ground the vertical line *v* five times, at the end of which a ground is given also to the rotary line *r*. When now, an impulse is given to the vertical line *v*, it passes through the dotted position of the side switch 28 and through line 38. Relay 39 thus being energized, will pull down the armature 47, and force the spring 48 to make contact with the spring 49. The spring 49, as shown, is connected directly with the ground side of the battery. The spring 48 on the other hand is connected to spring 50 of the private magnet 32, through which it makes contact with the spring 51, and from thence through the vertical magnet 36 with the main side of the battery 24, through the wire shown in dotted lines at 52. It is therefore clear that every impulse of the vertical line *v* closes the circuit of the vertical magnet 36, causing the shaft to step up one position in a manner well understood. After the desired number of impulses are given over the vertical line, an impulse is also given over the rotary line *r*. This passes through the dotted position of the side switch 29 to relay 45, drawing the armature 53 of said relay downwardly. The spring 54 is thereby forced against the ground spring 49, and this impulse passes through wire 55 to the private magnet 32, which is directly connected through 43 to the main side of the battery. When the armature 56 of the private magnet 32 is pulled down, it breaks contact of the springs 51 and 50, thereby opening the circuit of the vertical magnet 36. At the same time, it allows the side switch as a whole to slip into its second position in a manner well understood. Referring now to said side switch, the pole numbered 30 thereof is in its second position, making connection through 57 with 55, and hence with the private magnet 32. Pole numbered 31 in its second position makes connection with the ground side of the battery 24 through wire 58 and wire 59, the latter being connected through the interrupter spring 60 with the rotary magnet 37. As is well known, the armature 61 of this rotary magnet 37 is so arranged that whenever it is pulled down, it breaks the circuit of the magnet in the manner of an ordinary vibrating bell. Every time the armature is pulled down, however, it causes the wipers to rotate one position. Consequently, whenever the side switch is 130

left in the second position, the circuit is completed through the battery, and the said magnet and the wipers will continue to rotate, as long as said side switch is left in that position. As soon, however, as wiper 35 makes contact with a line that is not grounded, the circuit through the private magnet 32 is broken, and the side switch slips from the second position into the third, thereby also 10 breaking the circuit of the rotary magnet 37, and stopping the rotary motion of the wipers.

Referring to the side switch now in its third position, that is in the position it holds after the first selector has done the work, the 15 vertical line v is connected through pole 28 of said side switch, and line wiper 33 with a trunk line 62, leading to the second selector B. The connection of the line v is therefore completely broken from the relay 39 of the 20 first selector, and in the same manner the rotary line r from the calling station connects through 29 of the side switch and line wiper 34 with a trunk line 63 leading to the same second selector, relay 45 being in like manner 25 cut out of the rotary line, and its connection with the calling instrument. The operation of the second selector is very similar to that of the first, the only difference being that it is not supplied with a cut out relay corresponding to the relay 42, the relays corresponding to the relays 39 and 45 being connected directly with the main side of the battery. These relays, which are designated respectively 64 and 65 are provided with 30 extra springs 66 and 67, so adjusted that they will not make contact with either one of the armatures pulled down, but do make contact when both armatures are operated at the same time. The wipers of this second selector are designated respectively 68, 69 and 40 70. As already stated, this second selector operates in the same manner as the first selector just described, and consequently when an impulse is given by the calling device 45 after the first selector has operated, such impulse will pass over the vertical line v , through side switch 28, the line wiper 33, the trunk 62 to the side switch of the second selector B, and its relay 64, causing it to operate in the same manner as the first selector. Having thus operated, the trunk line 62 is 50 connected with the line wiper 68 of the second selector, and thereby with a trunk line 71 leading to the connector C. In the same manner, the rotary line r of the calling station is connected through the side switch 29 of the first selector, the line wiper 34 and the trunk line 63 to the second pole of the second selector side switch, and thereby through the 55 wiper 69 with the trunk line 72, leading to the connector C.

As is well known, the connector differs from the first selector, and second selector in that it does not rotate automatically, but is 60 caused to rotate step by step with the calling

device. It will be noted that the trunk lines 71 and 72 do not connect with the line relays 23 and 74 through side switches, as in the case of the first and second selectors, but are connected directly thereto, the first and second poles 75 and 76 of the side switch being connected to the lines 71 and 72 through two condensers 77 and 78. When therefore an impulse is given by the calling device after the operation of the first and second selectors, it passes over the trunk line 71 to the vertical relay 23. This closes the contact springs 79 and 80, 80 being connected directly to the ground side of the battery 24. 75 79 is furthermore connected with the private armature spring 81, and from there through lines 82 and pole 83, which is in its first position, making contact with the vertical magnet 84. An impulse over the vertical line 80 when the connector is in the normal position 85 will therefore cause the shaft to move step by step in the same manner as the shaft of the first selector. When the required number of impulses are given over the vertical line, the impulses that pass over the rotary line will in 90 the same manner pass through trunk 72 to relay 74 of the connector. This causes spring 85 to connect with ground spring 80 when the circuit through private magnet 86 is completed, causing the armature 87 thereof to be 95 pulled down, and thereby allowing the side switch to slip into its second position, as already described in connection with the first selector. When the side switch is in said second position, the circuit is broken with the 100 vertical magnet 84, and instead connected through wire 88 with the rotary magnet 89, whence on the next vertical impulse given to the line, the closing of the circuit by springs 79 and 80 of relay 73 will cause an impulse to 105 be given to rotary magnet 89, causing the shaft carrying the wipers to rotate step by step. The next impulse over the rotary line again closes the circuit of private magnet 86, and allows the side switch to slip into its 110 third position, thereby breaking all contact with the vertical and rotary magnets of the switch.

Referring now to the side switch 75 of the connector, it is found to be connected through the condenser 77 with the vertical trunk line 71. This side switch 75 is also now connected by the wire 90 with the spring 15, of the ringing relay 19, and wire 14 to the wiper 3 of the connector C, which is the corresponding wiper in Fig. 1 of the drawings. The side switch 76 is, as already stated, connected to the rotary trunk line 72 through condenser 78, and now being in its third position, is connected through wire 91 with wiper 4. The third pole 92 of the side switch of the connector being in its third position, is connected through wire 93, and wire 80 with the ground side of the battery 24, thereby grounding wire 94, and wiper 95 of connector. 130

This also grounds the cut out relay 96 of the first selector of the called subscriber, which separates the contact springs thereof that connect the main battery with the relays 97 and 98. Again the fourth pole 83 of the side switch of the connector, being in its third position, connects wire 82 with wire 99 to ringing relay 19, which is connected with the main side of the battery.

- 10 As a consequence, after the selection is completed, an impulse over the vertical line will cause the relay 23 to connect the spring 79 and 80, thereby closing the circuit of the ringing relay through spring 81, wire 82, switch 83, and wire 99. When the armature 20 of relay 19 is pulled down, it connects wire 14 with the generator, which sends the ringing current through wiper 3, normal wire 12, line wire 6, ringing the bell at station E in the 15 manner described in connection with Fig. 1 of the drawings. It will be noticed that this ringing current cannot in any manner affect the first selector G of the called subscriber, as the relays of such selector are disconnected 20 from the line by cut off relay 96. If the other member of the two party line is called, the wipers 3, 4 and 95 will then engage the contacts which are bridged in reverse order, so that a ringing current will then go over the 25 other line wire 5, and through the other bell 7 of the station D. It will thus be noted that after the selection is completed, the circuit is the same as represented in Fig. 1.

A modification, and probably the preferred embodiment of the invention, is illustrated in Fig. 2. Since each section of the ordinary Strowger switchboard is made up of one hundred selectors and there are one hundred contacts for the connector switches, 35 the most convenient method of bridging two wires to a line is perhaps by connecting the corresponding contacts of two different sections. Thus, in Fig. 2, A' designates a connector switch that connects with one series 40 of lines, numbered, say, from 1199 to 1300, and includes banks of contacts 1^a and 2^a, with which the wipers 3^a and 4^a co-operate. Another connector switch B' connects with 45 another series of lines, numbered, say, 1299 to 1400 and includes contacts 1^b and 2^b, with which the wipers 3^b and 4^b co-operate. A party line is shown as composed of wires 5^a and 6^a, on which are located the stations C' and D', respectively designated 1201 and 50 1301, and having bells 7^a and 8^a. Each of the bells is connected to one line wire only and is grounded, as illustrated at 9^a. Now the first contacts 1^a and 2^a are respectively connected to the line wires 5^a and 6^a by the 55 wires 11^a and 12^a, while the corresponding contacts 1^b and 2^b of the other connector switch are respectively connected in a reverse manner by the wires 13^b and 14^b to the wires 6^a and 5^a.

65 A ringing current generator is shown at

15^a, the switches 15^b of which are connected respectively with the wipers 3^a and 3^b by the wires 17^b. Associated with the connector switches are the usual ringing relays 16^a and 16^b. The wipers of a second selector switch 7^a are illustrated at 17^a and 18^a, the same being movable into coaction with the contacts 19^a and 20^a of the connector switch A', and the contacts 19^b and 20^b of the connector switch B'. A calling station E', having a signal button 21^a is shown as connected by the wires r' and v' through a first selector switch F' to the second selector switch. If, now, the station E' calls C' or "1201," the wipers 17^a—18^a of the second selector switch will 80 assume the relation shown, and the wipers 3^a and 4^a of the connector switch A' will connect with the line wires 5^a and 6^a, so that a signal from the calling station will cause the current from the generator 15^a to pass 85 through the line 11^a and thence through the bell 7^a. If, however, station D' or "1301" is called, the wipers 17^a—18^a will contact with 19^b and 20^b, while the wipers 3^b and 4^b will respectively engage the contacts 1^b and 2^b, with which the line wires 5^a and 6^a are connected. Therefore, upon the operation of the signal button of the calling station, the ringing relay 16^b will operate to throw the generator 15^a into circuit with the line 6^a, 95 and thus the bell 8^a will be rung. It will be observed that this arrangement has all the advantages and is directly along the lines of the first-described embodiment, for in this form also the usual wipers are made to carry 100 the ringing current to either wire and but one ringing relay is necessary for each connector and all the lines associated therewith.

From the foregoing it is thought that the construction, operation, and many advantages of the herein described invention will be apparent to those skilled in the art, without further description, and it will be understood that various changes in the size, shape, proportion, and minor details of construction 110 may be resorted to without departing from the spirit or sacrificing any of the advantages of the invention.

Having thus described our invention what we claim as new and desire to secure by Letters Patent, is:

1. In an automatic telephone exchange system, the combination with a party line including two wires, of party signals, each of which is connected to one only of the wires, 120 ringing current-generating means, and line-selecting mechanism including wipers connecting the generating means to either of the wires of the said party line and constituting part of the ringing current carrying means 125 between the generating means and the signals.

2. In an automatic telephone exchange system, the combination with a party line including two wires, of party signals, each of 130

- which is connected to one only of the wires, ringing current-generating means, line-selecting mechanism including contacts bridged to the wires of the party line, and wipers 5 operating with the contacts and having connections with the generating means to electrically connect the same to either wire of said party line, said wipers constituting part of the means for carrying the ringing current 10 from the generating means to the signals.
3. In an automatic telephone exchange system, the combination with a party line including two wires, of party signals connected respectively to the wires, ringing current-generating means, line-selecting mechanism including banks of contacts, certain of said contacts being bridged to the wires of said party line, wipers operating over said contacts, and connections between the wipers 15 and current-generating means to cause the connection of the latter to either wire of the line, said connections being independent of the line wires.
4. In an automatic telephone exchange system, the combination with a plurality of lines including a party line having two wires, of party signals, each of which is connected to one of the wires and is grounded, ringing current-generating means also grounded, line-selecting mechanism including contacts, 20
- wipers operating thereover, bridge connections between certain of the contacts and the different wires of the party line, and electrical connections between the generating means and the wipers that engage the bridged contacts, said connections being separate from the line wires. 25
5. In an automatic telephone exchange system, the combination with a plurality of lines including a party line having two wires, of party signals, each of which is connected to one only of the wires, line-selecting mechanism including selector and connector switches that co-operate with the different lines, ringing current-generating means electrically connected to the selecting mechanism, and bridging connections between the party line wires and the connector switches, whereby the generating means may be electrically connected to either wire independently of the other. 30
- In testimony, that we claim the foregoing as our own, we have hereto affixed our signature in the presence of two witnesses.

JOHN WICKS.
DONALD D. MCKAY.
